UNITED STATES PATENT OFFICE.

ANTENOR ASSORATI, OF NEW YORK, N. Y.

WINDOW.

No. 844,229.

Specification of Letters Patent.

Patented Feb. 12, 1907.

Application filed January 5, 1906. Serial No. 294,707.

To all whom it may concern:

Be it known that I, ANTENOR ASSORATI, a subject of the Crown of Italy, and resident of the borough of Manhattan, in the city and 5 State of New York, have invented a new and useful Improvement in Windows, of which the following is a specification.

My invention relates to improvements in swinging windows, and has more particularly 10 for its object to provide certain novel features in the construction, form, and arrangement of the several parts whereby the upper and lower sashes may not only be raised and lowered, but may also be swung into different 15 inclined positions with respect to the window-frame.

In the accompanying drawings, Figure 1 is a front view of the window looking from the interior. Fig. 2 is a vertical central section 20 through the same with the parts in their normal positions arranged to permit the sashes to slide vertically. Fig. 3 is a similar section showing the parts in the positions which they assume when the sashes have been swung out 25 at substantially right angles to the window-frame. Fig. 4 is an enlarged detail view of the means for pivoting one of the sashes. Fig. 5 is a similar view showing certain of the 30 parts in section to more clearly illustrate the means for yieldingly holding the pivot-bolt in its extended or withdrawn position. Fig. 6 is a detail sectional view showing the means 35 for locking the front strip to the window-frame. Fig. 7 is a front view of this locking means. Fig. 8 shows a plate on the front strip 40 for engaging the locking means carried by the window-frame. Fig. 9 is a detail section showing the manner of hinging the parting-strip to the frame. Fig. 10 is a detail section 45 showing the means for locking the parting-strip in its vertical position; and Fig. 11 is a front view of said locking means.

The window-frame is denoted as a whole by 1, in which frame are fitted to slide vertically the upper and lower sashes 2 and 3. The lower horizontal front strip, which is located along the sill, is denoted by 4, and the upper horizontal front strip is denoted by 5. The side front strips comprise upper station- 50 ary sections 6 and 7, intermediate hinged sections 8 and 9, arranged to swing in a plane at right angles to the plane of the window-frame, and lower hinged sections 10 and 11,

arranged to swing in the plane of the window-frame. These lower sections 10 and 11 are 55 so hinged as to permit the sections when released to fold one on top of the other and on top of the lower horizontal front strip 4. The meeting ends of the intermediate sections 8 9 and lower sections 10 11 are tongued 60 and grooved, as shown at 12, so that the intermediate sections cannot be swung away from the window-frame until the lower sections have been swung downwardly.

The parting-strips comprise two permanent upper sections 13, two, intermediate hinged sections 14, arranged to swing in a plane at right angles to the plane of the window-frame, and two lower hinged sections 15. The meeting ends of the intermediate and lower sections 14 15 are tongued 70 and grooved, as shown at 16, so that the intermediate sections cannot be swung away from the window-frame until the lower sections are swung downwardly. 75

Each of the lower sections 10 and 11 of the front strips is removably locked in its vertical position by the following device: A casing 17 is secured in the face of the window-frame—as, for instance, by fastening-screws 80 18. This casing has a latch 19, hinged at 20 therein, which latch is arranged to swing into and out of the said frame. This latch 19 is provided with a shoulder 21, arranged to be engaged by the finger of the operator to 85 throw the latch into a position extending outwardly from the frame. This latch 19 is provided with a cross-head 22. The lower section of the front strip is provided with a hole 23 therethrough, and it is also provided 90 with a plate 24, having a hole 25 of sufficient size to permit the insertion of the head 22 of the latch therethrough, which hole is provided with a narrowed portion 26 of sufficient size to permit the latch back of the head 95 to enter the same, and thus permit the latch to lock the strip in position. Each of the lower hinged sections 15 of the parting-strip is also held in its vertical position by a similar fastening means, the details in construction of which are slightly different to adapt 100 it to its particular position in the window-frame.

To permit the lower sashes to be swung away from the window-frame when so desired, I provide the sides of the window- 105

frame with sockets 27 adjacent to the points where the intermediate front sections 8 and 9 are hinged to the window-frame and provide the top rail 28 with flush-bolts 29, arranged 5 to enter said sockets 27 when extended. These bolts are fitted to slide in suitable 10 housings 30, secured in the top rail 28 of the lower sash. Springs 31 are arranged in position to yieldingly hold the bolts in their extended or withdrawn positions.

The upper sash may be hinged to swing away from the window-frame when so desired by providing the sides of the window-frame with sockets 32 adjacent to the places 15 where the intermediate sections 14 of the parting-strips are hinged to the frame and providing the top rail 33 of the upper sash with flush-bolts arranged to enter said sockets when extended, the said bolts being quite 20 similar in construction and operation to the bolts 29 in the top rail of the lower sash.

A very neat and unobtrusive device is provided for holding the sashes swung away from the frame, which device comprises an 25 upper rigid section 34, an intermediate section 35, hinged thereto, and a lower flexible section 36. This upper section 34 is hinged at 37 to the window-frame and when not in use is arranged horizontally along the under side 30 of the top of the frame and held temporarily in position by a hook 38. The intermediate and lower sections 35 36 when not in use hang vertically along the sides of the window. This intermediate section 35 is provided with 35 a hook 39, which may engage with an eye 40 in the bottom rail 41 of the lower sash 3. The flexible lower section 36 is provided with a hook 42, arranged to engage an eye 43 in the bottom rail 44 of the upper sash 2.

40 In operation, supposing the window to be in its normal position for use, with its sashes sliding vertically, and it be desired to swing the sashes away from the window-frame for purposes of ventilation, cleaning, 45 or any other cause, the method of procedure would be as follows: The lower sections 10 and 11 of the front strips would be released from their fastening means and swung down into proximity to the horizontal front strip 50 4. The lower sash would then be raised until its side bolts carried by the top rail of the lower sash could be extended into the 55 sockets 27. This lower sash could then be swung outwardly and at the same time swing the intermediate sections 8 and 9 of the front strips outwardly with it. The sash-holding device could then be released from its hook 38 and have its hook 39 engage with the eye 40, thus holding the lower 60 sash in position. The lower sections 15 of the parting-strips could then be released from their fastening device and swung downwardly into proximity to the window-sill. The upper sash could then be lowered

until its side bolts could be extended into 65 the sockets 32 in the window-frame, the intermediate sections 14 of the parting-strips being swung away from the window-frame into positions beneath the lower sash. The upper sash could then be swung away from 70 the window-frame and held in position by the engagement of the hook 42 with the eye 43.

It will thus be seen that a very simple and effective arrangement is provided for permitting the very rapid manipulation of the parts, so that the sashes may be used to slide vertically, as is common, or be swung away from the window-frame.

What I claim as my invention is—

1. A window-frame, its upper and lower sashes fitted to slide vertically and to swing away from the frame, the side front strips of the frame comprising upper stationary sections, intermediate hinged sections arranged to swing in a plane at right angles to the plane of the frame and lower hinged sections arranged to swing in the plane of the frame, the meeting ends of the intermediate and lower sections being so interlocked that the intermediate sections cannot be swung away from the frame until the lower sections have been swung downwardly, and means for removably locking the lower sections of the front side strips to the frame in 95 their vertical position.

2. A window-frame, its upper and lower sashes fitted to slide vertically and to swing away from the frame, the side front strips and the parting-strips of the frame comprising upper stationary sections, intermediate hinged sections arranged to swing in a plane at right angles to the plane of the frame and lower hinged sections arranged to swing in the plane of the frame, the meeting ends of the intermediate and lower sections of the side front strips and of the bearing-strips being so interlocked that the intermediate sections cannot be swung away from the frame until the lower sections have been swung downwardly and means for removably locking the lower sections of the side front strips and of the parting-strips to the frame in 110 their vertical position.

3. A window-frame, its upper and lower 115 sashes fitted to slide vertically and to swing away from the frame, and a device for supporting the sashes when swung away from the frame comprising an upper rigid section, an intermediate rigid section and a lower 120 flexible section.

4. A window-frame, its upper and lower sashes fitted to slide vertically and to swing away from the frame, and a device for supporting the sashes when swung away from 125 the frame comprising an upper rigid section, an intermediate rigid section and a lower flexible section, the said window-frame be-

ing provided with means for supporting the device with the upper section arranged along the top of the frame and the intermediate and lower sections arranged along the 5 sides of the frame when the device is not in use.

In testimony that I claim the foregoing as

my invention I have signed my name, in presence of two witnesses, this 3d day of January, 1906.

ANTENOR ASSORATI.
